KEYBOARD

Hans Luedtke, Berlin-Tempelhof, Germany

Application June 8, 1933, Serial No. 674,957
In Germany June 8, 1932

11 Claims. (Cl. 84—423)

The present invention relates to a keyboard system and more particularly to a keyboard which is combined with electrical contacts or relays and which is not alone adapted for use in connection with normal musical instruments, such as for instance organs, fortepianos or orchestrion-like instruments, but also as a register keyboard for the works of organs and the like. The novel keyboard may further be used for recording sound 5 on sound films by means of a photoelectrical cell, for recording sound in the form of note writing, for instance in the form of or substantially in the form of modern orchestra scores. The invention may also be used in combination with typewriters, 10 calculating machines, cash registers, line selectors in telephone exchanges and for operating type printers and other apparatus employed in modern communication systems.

According to the invention the keys can not 20 only as usual be arranged in a horizontal plane but also in a vertical plane or in planes of any desired inclination. The keys are all exactly or substantially of the same shape. Preferably the key heads have the form of honeycombs. When 25 key heads of this form are used the play field or number of keys in a group may easily be increased in all directions. The effect exerted by the individual keys may in accordance with the invention be altered by means of an electrical 30 switching device. If for instance an A key, when depressed, at a certain position of the switch will produce a violin tone the same key may be caused to produce for instance a tone having the character of a pianoforte tone simply by changing 35 the position of the switch. The invention also comprises means which makes it possible to change over from one tone system to another.

Some constructional forms of the invention are illustrated by way of examples in the accompanying 40 drawing.

Fig. 1 shows a portion of a keyboard in plan view.

Fig. 2 shows, also in plan view, a portion of a modified form of keyboard.

Fig. 3 is a vertical sectional view showing a key 45 and an electrical contact device operated by the same.

Fig. 4 is a horizontal sectional view taken on line 4—4 in Fig. 3.

Fig. 5 is a sectional view showing the cross-sectional form of the key heads.

Fig. 6 is a lateral plan view showing a key head.

Fig. 7 is a plan view of the same key head.

The portion of a keyboard shown in Fig. 1 consists of 16 keys 50 which are arranged in such a

manner, that a continuous field is formed. The keys are grouped in four oblique and parallel rows of which each contains four keys. This keyboard is designed for musical purposes. As indicated by legends the individual keys control tones of the common tone or note system which is used over the entire civilized world and according to which the musical tones are grouped in octaves of which each consists of twelve semitones. When comparing the keyboard section 10 shown with the keyboard of a modern pianoforte it will be seen, that the three lower horizontal rows of keys of this section contain all tones of an octave. Some of these tones are represented for a second time in the uppermost row 15 which also contains the first tone of the next octave.

The section of a keyboard shown in Fig. 2 consists of 20 keys which together form a continuous field. The keys are grouped in four oblique and 20 parallel rows of which each contains five keys. Two keys in the upper right corner of the keyboard section carry no legends. These keys may for instance be used for operating master switches or the like. The individual keys of this keyboard 25 are intended to control the tones of a tone system consisting of eighteen third tones.

The individual keys or groups of keys may of course be grouped in any desired manner and may be arranged for any tone system, for instance for a tone system consisting of series of 30 24 quarter tones, without the scope of the invention being surpassed. As already mentioned the keyboard arrangement according to the invention may be employed for musical purposes of 35 different kinds, for instance for organ registers which are grouped in manuals, and for a great variety of recording, reproducing, registering and controlling purposes.

A preferred embodiment of the novel keyboard, 40 which is adapted for use in combination with all today imaginable musical instruments and in which, therefore, each section or unit covers an octave, has a front row consisting of four keys which are arranged adjacent each other. The 45 other keys are arranged behind this front row in honeycomb-like relation. Keyboards used for other purposes, for instance keyboards used in connection with the registers or organs or calculating machines, may of course be otherwise arranged and the front row of each unit may for instance consist of five or seven keys. On account of the honeycomb-like arrangement of the key heads the fingers may be passed from one key to another without lifting them from the keyboard. 50 55

Accords, double strokes and the like with constant interval distances may therefore be performed "glissando" i. e. slidingly, without altering the fingering.

- 5 It will be evident, that the fingering must be changed, on passing over from one octave section to another, if the second section is lying to the right or left of the first section. It is however also within the scope of the invention to arrange 10 a second section also behind the first one. Groups of keys or keyboard sections may be added to the existing in all directions. It is in other words possible to build up a play field of almost infinite dimensions.
- 15 In such cases a plurality of keys of the same significance or character must be present in each unit. For instance in keyboards for musical purposes each tone of the scale must be represented by a plurality of keys. Keyboards of this kind 20 may be arranged without difficulties since the keys according to the invention cooperate directly with electrical contacts and relays, so that no lever mechanisms or the like are involved and the travel or stroke of the keys is much shorter 25 than at the operating mechanism of the normal musical instruments.

According to the invention means are provided which makes it possible to alter the effect exerted by the key and for instance during the playing 30 to switch over from a tone system consisting of series of twelve semitones to a system consisting of series of eighteen third tones or from a 16' to an 8' or to a 4' organ tone and the like. These means comprise master switches adapted to influence all unit sections (octave sections, organ 35 manuals or the like) of the keyboard. A single master switch may be used for influencing one, several or all sections or each section may be equipped with a plurality of master switches. By 40 means of these switches each individual key may be caused to make contact with a great variety of different contacts and consequently to create different sound effects.

In fortepianos and the like when a key is depressed 45 the movement is transmitted by means of complicated lever mechanisms. In contrast hereto the keys according to the invention act directly upon the electrical contacts in the direction in which they are depressed without the 50 use of any intermediate mechanical devices.

The key shown in Figs. 3 and 4 consists of a key head 1 and a shank part 6. The shank part 6 is located in a sleeve 7, which again is fixed in a support plate 8. The shank is equipped with a 55 projecting pin 9 adapted to slide in a groove 10 in the sleeve 7 and near the lower end of the shank a stop ring is fixed which limits the upward movement of the key. 2 and 2' denote two co-operating contact members. When the key is depressed against the force of the spring 3 the pin 9 will press contact member 2' against contact 2, whereby a circuit is closed.

Fig. 5 is a cross-sectional view of the keyboard shown in Fig. 1. As will be seen the surface of the key heads lying behind each other are curved in such a manner, that the fingers easily may 65 slide from one row of keys onto the next.

As will be seen from Fig. 6 (and also from Fig. 5) the surface of each key head consists of two 70 finger contact faces 4 and 5, which form a flat angle with each other. When the surface of the key heads is formed in this manner one or more fingers may always be moved slidingly i. e. glissando from one key to the next.

75 Fig. 7 shows the relation between both finger

contact faces of a key head. The foremost and larger part 4 is of curved shape and the part 5 consists of a depression or groove the edges of which preferably are parallel or substantially parallel to the base of the key head.

5 The invention is not only suited for use in combination with manually operated keyboards. Similar arrangements may with the same advantage be used as pedal keyboards, i. e. instead of the usual organ pedals. Also in this case the 10 front of each octave section consists of four keys and the dimensions of a pedal may be reduced to such a degree, that the total area of a pedal with a normal number of keys is only the half of the 15 area of the organ pedals hitherto known. A pedal area which hitherto was played with two feet can therefore now be operated with a single foot. Moreover, when organ pedals are arranged in accordance with the present invention also 20 chords such as for instance thirds may be made, and tones which are separated by so large an interval, that they can not be played legato when normal pedals are used, can now be played absolutely legato.

25 Various modifications may be made in the invention without departing from the spirit thereof or the scope of the claims and therefore the exact forms shown are to be taken as illustrative only and not in a limiting sense, and I desire therefore, that only such limitations shall be 30 placed thereon as are imposed by the prior art or are specifically set forth in the appended claims.

I claim:—

35 1. A keyboard comprising keys with substantially uniformly shaped hexagonal key heads in honeycomb-like formation arranged in a single general plane adjacent each other and in close relation, thereby forming a continuous field, adapted to be extended after desire in all directions and to be subdivided in any desired manner, the surface of each key head being inclined towards its edges so as to secure a smooth passage from each key head to the surrounding ones.

40 2. A keyboard comprising keys with substantially uniformly shaped hexagonal key heads in honeycomb-like formation arranged in a single horizontal plane adjacent each other and in close relation, thereby forming a continuous field adapt- 45 ed to be extended after desire in all directions and to be subdivided in any desired manner, the surface of each key head being inclined towards its edges so as to secure a smooth passage from each key head to the surrounding ones.

50 3. A keyboard comprising keys with substantially uniformly shaped hexagonal key heads in honeycomb-like formation arranged in a single vertical plane adjacent each other and in close relation, thereby forming a continuous field adapt- 55 ed to be extended after desire in all directions and to be subdivided in any desired manner, the surface of each key head being inclined towards its edges so as to secure a smooth passage from each key head to the surrounding ones.

60 4. A keyboard comprising keys with substantially uniformly shaped hexagonal key heads in honeycomb-like formation arranged in a single general plane of any desired inclination adjac- 65 ent each other and in close relation, thereby forming a continuous field, adapted to be extended after desire in all directions and to be subdivided in any desired manner, the surface of each key head being inclined towards its edges 70

75

so as to secure a smooth passage from each key head to the surrounding ones.

5. A keyboard comprising keys with substantially uniformly shaped hexagonal key heads arranged adjacent each other in close relation, some of the keys being adapted, when operated, to alter the effect exerted by the other keys, the surface of each key head being inclined towards its edges so as to secure a smooth passage from 10 each key head to the surrounding ones.

6. A keyboard for musical purposes comprising keys with practically uniformly shaped hexagonal key heads in honeycomb-like formation arranged in a single general plane in close relation, thereby forming a continuous field consisting of sections of keys covering an octave, the front of each section being formed by a row 15 of four keys, the surface of each key head being inclined towards its edges so as to secure a smooth 20 passage from each key head to the surrounding ones.

7. A keyboard for musical purposes comprising keys with practically uniformly shaped hexagonal key heads in honeycomb-like formation arranged in a single plane in close relation, thereby forming a continuous field consisting of units 25 of keys covering a definite range of tones, certain tones being represented more than once in each unit, the surface of each key head being 30 inclined towards its edges so as to secure a smooth passage from each key head to the surrounding ones and allow a glissando playing and unaltered fingerings when the fingers are moved over the keys.

35. 8. A keyboard for musical purposes comprising keys with practically uniformly shaped hexagonal key heads in honeycomb-like formation arranged in a single plane in close relation, thereby forming a continuous field consisting of units

of keys covering a definite range of tones, the surface of each key head consisting of two finger contact faces forming a flat angle with each other and allowing a glissando movement of the fingers from key to key.

9. A keyboard for musical purposes comprising keys with practically uniformly shaped hexagonal key heads in honeycomb-like formation arranged in a single plane in close relation, thereby forming a continuous field consisting of units 10 of keys covering a definite range of tones, the surface of each key head consisting of two finger contact faces, the foremost face being larger and of curved shape, the other face consisting of a circular depression the edge of which is lying in a plane substantially parallel with the plane through the edges of the base of the key head.

15. 10. A keyboard for musical purposes comprising keys with hexagonal key heads in honeycomb-like formation arranged in a single plane in close relation, thereby forming a continuous field consisting of units of keys covering a definite range of tones, the surface of each key head consisting of two finger contact faces forming a flat angle 20 with each other and allowing a glissando movement of the fingers from key to key, some of the keys being adapted, when operated, to alter the effect exerted by the other keys.

25. 11. A keyboard particularly for organ pedals 30 and the like, comprising keys with practically uniformly shaped hexagonal key heads arranged in a single general plane in close relation, thereby forming a continuous field, said keys being dimensioned so as to allow the entire field to be 35 operated by a single foot and the heads of the keys being so arranged and formed, that widely separated tones may be played legato.

HANS LUEDTKE.
